To all whom it may concern:

Be it known that I, LOTHIAR VON GRAVE, a subject of the King of Prussia, residing at Wallingford, Connecticut, have invented and produced a new and original Design for Picture-Frames, of which the following is a specification, reference being had to the accompanying drawing, wherein the figure shows a face view of a frame illustrating my design, one-half only of said view being shown in full lines, the other half being shown in outline.

The essential features of my design consist in a central elliptical portion surrounded by an openwork leaf-like portion with chasing thereon, and following the general contour of the central portion.

In the drawing a represents a central ornamental elliptical portion, with the opening b therein. Surrounding this elliptical portion a is an openwork leaf-like portion c having d chasing thereon and following the general contour of the central elliptical portion a. 20

The design for a picture frame substantially as shown and described.
